Primary Examiner — Robert M. Spear*Assistant Examiner* — John A Voytek(74) *Attorney, Agent, or Firm* — Boyle Fredrickson, S.C.(57) **CLAIM**

The ornamental design for a basin, substantially, as shown and described.

DESCRIPTION

FIG. 1 is a raised perspective view of a basin having mounted thereon a pair of lavatory fixtures;

FIG. 2 is a rear perspective view of the basin of the embodiment as shown in FIG. 1;

FIG. 3 is a front view of the basin of the embodiment as shown in FIG. 1;

FIG. 4 is a rear view of the basin of the embodiment as shown in FIG. 1;

FIG. 5 is a top view of the basin of the embodiment as shown in FIG. 1; and,

FIG. 6 is a side view of the basin of the embodiment as shown in FIG. 1.

Any broken lines represent environmental structure and form no part of the claimed design.
